UNITED STATES PATENT OFFICE.

WILLIAM STEPHEN BOYCE, OF CHICAGO, ILLINOIS.

TIE PLATE.

Application filed November 17, 1923. Serial No. 675,259.

REISSUED

To all whom it may concern:

Be it known that I, WILLIAM STEPHEN BOYCE, a citizen of the United States, residing at Chicago, in the county of Cook and State of Illinois, have invented certain new and useful Improvements in Tie Plates, of which the following is a specification, reference being had to the accompanying drawings, and to the reference characters marked thereon, which form a part of this specification.

This invention relates to an improvement in tie plates of the general type known in the trade as "compression" plates; such, for example, as illustrated in United States Letters Patent No. 1,219,224, issued to Edwin H. Bell, on March 13th, 1917.

Compression tie plates are characterized by having on a portion of their under or bottom surface, transverse, pointed, tie-engaging ribs and between these ribs, a plurality of parallel, arcuate undulations or depressions, extending lengthwise of the plate and of the tie, and which intersect in lines to form intermediate, parallel ribs extending in the plane of the bottom of the plate and lengthwise thereof. These latter ribs enter the tie between the fibres of the tie and by reason of the curved, arcuate surfaces, compress the fibres together and hence the trade-name "compression" tie plates.

While the tie plate of the said Bell patent possesses certain advantages and improvements in the art, it has nevertheless demonstrated in use in track that the sharpened, transverse bottom ribs between which the arcuate depressions extend, actually cut or sever the fibres of the wood when the plate is being seated in the tie. This action of the ribs which are transverse to the grain of the tie is considered by some engineering experts in railroad track construction to be a disadvantage in that it tends to the premature destruction of the tie and also requires a relatively longer period of use in track before the plate becomes properly seated on the tie for prolonged use. During this period and before the plate becomes securely imbedded in the tie, it shifts, more or less, and wobbles on the tie under the "wave motion" and thrusts and strains of the rails due to train movements thereon.

The main object of my invention is to produce a tie plate having its bottom surface so constructed as to retain all the advantages of the compression grooves or un-

dulations, while overcoming the objections above referred to, and at the same time producing other advantages.

Another object of my invention is to produce a tie plate, the under surface of which is free from all sharp or fibre cutting ribs or edges, while at the same time is possessed of parts adapted to readily enter the tie and seat the plate firmly thereon.

Another object is to strengthen tie plates of this type at those points where they are subjected to bending or breaking strains; in other words, to produce a compression type of plate having the minimum of metal and the maximum of rigidity and strength against the buckling or breaking strains to which it will be subject, combined with maximum efficiency in the performance of its intended functions.

These and other advantages will appear as I proceed with the description of my improved tie plate.

In the drawings:

Fig. 1 is an elevation or side view of a tie plate constructed in accordance with my invention.

Fig. 2 is a bottom plan view of the same.

Fig. 3 is a vertical, longitudinal, sectional view through the plate, the section being in the plane of the dotted line 3—3 of Fig. 2.

Fig. 4 is a vertical, transverse, sectional view of the tie plate, the section being in the plane of the dotted line 4—4 of Fig. 3.

Fig. 5 is a perspective view, on a smaller scale, of a railroad tie showing the adz-man's work preparatory to placing a tie plate thereon.

Figs. 6 and 7 are sectional views, similar to Fig. 3, showing the two positions the tie plate assumes upon the tie, as hereinafter more fully explained.

Referring now more in detail to that embodiment of my invention illustrated in the accompanying drawings, A represents the tie plate as a whole, the same being of the conventional, rectangular, oblong shape, having a flat rail bearing top surface 1, a transverse rail abutting shoulder 2, and inclined or tapered top end portions 3 and 4. B represents a conventional wooden tie as a whole, having its top surface adzed or cut away, as at 5, for the reception of a tie plate.

The bottom of the plate A is provided with two spaced apart, transversely arranged, flat, tie bearing surfaces 6, 6. In that part

of the bottom surface of the plate between these transverse surfaces 6, 6, there are formed a plurality of parallel, arcuate undulations, depressions or grooves 7, 7, which 5 are comparatively flat or shallow. These grooves extend at right angles to the said bearing surfaces 6, 6, that is to say, lengthwise of the plate. The inner edges 8 of the surfaces 6, 6, extend at an angle to the surface and terminate in a curve, both at the top and bottom. Thus a rounded corner is formed at the top, as indicated at 9, and a fillet 10 is formed at the bottom between the edge 9 and the surface of the groove 7.

15 The bottom surfaces 11, 11, of the plate, beyond the outer edges of the bearing surfaces 6, 6, are formed on a different, but parallel plane to the plane of the bearing surfaces 6, 6. When the bearing surfaces 20 6, 6 rest upon the tie, a small space, indicated in Fig. 6 at 12, separates the surfaces 11 from the top surface of the tie B. The surfaces 6, 6, are made with rounded corners 13 along their outer margins, and the ends 25 of the plate are likewise rounded as indicated at 14.

The arcuate surfaces of the depressions or grooves 7 intersect in a plurality of parallel lines in the plane of the bearing surfaces 6, thereby forming a plurality of 30 parallel ribs 15 extending lengthwise of the plate intermediate the two bearing surfaces 6, 6. These ribs 15 thus run parallel with the grain or fibres of the wood of the tie 35 when the plate A is placed thereon for use. The plate may have spike holes 16, if desired.

It is common practice in track construction, in the laying of new ties in the road 40 bed and also in the relaying of plates and rails upon old ties in track, to shape or fashion the top surface of the ties to receive the tie plate. This is done with an adz, by cutting away a portion of the surface, as indicated at 5 in Fig. 5, so that the plate will be more or less seated in the 45 cut-away space. If the adzman is not skilled, or if he is careless, this work results in the formation of an irregular space 50 5 so that the plate when first laid on the tie will rest upon spaced apart bearing surfaces in the tie. There being no intermediate support between such bearing surfaces, the plate is thus readily buckled or 55 bent by the passage of the train load over the rail and plate. These bearing surfaces may be projections, such as ribs transversely arranged on the bottom of the plate, or they may be, as in the case of a flat bottom 60 plate, the outer portions of the bottom surface, since the intermediate portion of the bottom of the plate would have no support by reason of the cut away portion 5 of the tie.

65 Referring to Fig. 6, it will be seen that

no such difficulty as just mentioned will occur with the laying of my improved tie plate in track, since, in the first instance, the surfaces 11, 11, of the plate do not rest upon the tie, and only the outer portions 70 of the bearing surfaces 6, 6, and their rounded marginal corners 13, 13, are in contact with the tie. When pressure is brought to bear upon the plate A by the workman in seating the plate or in spiking, or by 75 the passage of a trainload thereover, the plate will almost instantly imbed itself to a slight extent in the tie. The space 12 is quickly eliminated so that the surfaces 11, 11, rest upon the tie. The surfaces 6, 6, 80 are pressed down into the cut away portion 5 and this is more readily accomplished by reason of the fact that its outer corners are rounded, as at 13. At the same time, the ribs 15 begin to engage the tie, entering between the fibres thereof and by reason of the curved, arcuate surfaces of the grooves 7, 7, the fibres are spread apart as the tapered rib 15 continues to move into the tie, and compression of the fibres begins. 90 In use, the seating of the plate A on the tie B continues until the plate is driven into the tie so that the surfaces 11, 11, are slightly below the top surface of the tie, as indicated at 17 in Fig. 7. In this position, by reason of the construction above described, together with the spikes used in securing the rail to the plate and the plate to the tie, the plate A will be firmly seated upon and united with the tie B and will resist 95 all tendency to shift or wobble under train load and will lend itself to further depression into the tie as the use in track is 100 continued.

By reason of the fact that the grooves 7 extend lengthwise of the plate and are joined at their opposite ends to the bearing surfaces 6, 6, by the metal forming the fillets 10, a very strong construction is attained which resists distortion or buckling action by the 105 load transversely passing over the top surface of the plate.

When the plate is first placed upon the tie, with the surfaces 6, 6, only, resting thereon, the tendency to bend or buckle is resisted by the truss construction of a plurality of arched under surfaces intimately joined and cooperating with the longitudinal ribs 15. As the downward thrust continues, the ribs 15 and the surfaces 6, 6, will be entered further into the tie, the fibres being compressed together until a perfect union of plate and tie results. When this occurs, the load is 115 transmitted through the plate and the tie.

When tie plates break, the break usually 120 occurs at or adjacent to the juncture of the top surface and the rail abutting shoulder. Where the under side of the tie plate is provided adjacent to this location with sharpened ribs or fibre-cutting projections, it is 125 130

found that the plate has a greater tendency to break at this point. This objection and difficulty is entirely eliminated by the present invention, in the shaping of the marginal surfaces 8 of the bearing surfaces 6 into rounded corners and by the additional metal fillets 10 placed in the plate by joining the surfaces 8 with the arcuate surfaces 7, thus giving additional metal where metal is needed without appreciably increasing the weight of the plate.

It will, of course, be understood that while I have shown the rail bearing surface 1 to be flat, such surface may conform to any conventional or special configuration; the canted or the cambered top surface, for instance, coacting equally with my improvements in the bottom of the tie plate. These and other changes may be made if desired, provided the essential features of having the end bearing surfaces 11, 11, and the transverse bearing surfaces 6, 6, lie in different planes, and of having no fibre cutting points or edges in the plate of a compression type, being retained.

I claim as my invention:

1. A tie plate having on its bottom, intermediate its ends, two longitudinally spaced apart, relatively narrow bearing surfaces extending transversely from one side of the plate to the other, a plurality of curved, arcuate compression grooves extending longitudinally between said bearing surfaces, the ends of the plate bottom having flat tie engaging surfaces located beyond the bearing surfaces and in a different plane therefrom, and the arcuate surfaces of the grooves intersecting in a plane coincident with the plane of said bearing surfaces.

2. A tie plate having on its bottom, intermediate its ends, two longitudinally spaced apart, relatively narrow bearing surfaces extending transversely from one side of the plate to the other, a plurality of curved, arcuate compression grooves extending longitudinally between said bearing surfaces, the ends of the plate bottom having

flat tie engaging surfaces located beyond the bearing surfaces and in a different plane therefrom, and the arcuate surfaces of the 50 grooves intersecting in a plane coincident with the plane of said bearing surfaces, a curved strengthening fillet joining the compression grooves to the adjacent side margins of the bearing surfaces.

3. A tie plate, the tie engaging bottom of which comprises two transversely extending and longitudinally spaced apart tie bearing surfaces, a plurality of parallel, flattened, arcuate grooves or undulations between said bearing surfaces and extending lengthwise of the plate, the surfaces of said grooves or undulations intersecting to provide a plurality of parallel tie engaging ribs extending in the direction of the length of the plate and located in the plane of the said spaced bearing surfaces, and the bottom surfaces of the ends of the plate being in a different but parallel plane to the plane of the bearing surfaces and ribs.

4. A tie plate having on its bottom, intermediate its ends, two longitudinally spaced apart, relatively narrow bearing surfaces extending transversely from one side of the plate to the other, a plurality of curved, arcuate compression grooves extending longitudinally between said bearing surfaces, the ends of the plate bottom having flat tie engaging surfaces located beyond the bearing surfaces and in a different plane therefrom, 75 and the arcuate surfaces of the grooves intersecting in a plane coincident with the plane of said bearing surfaces, the bearing surfaces being provided with rounded corners throughout their length.

In testimony that I claim the foregoing as my invention I affix my signature, in the presence of two witnesses, this 13th day of November, 1923.

WILLIAM STEPHEN BOYCE.
